UNITED STATES PATENT OFFICE.

HARRY O'GRADY, OF WESTBOURNE, TENNESSEE.

TORPEDO-CATCHER AND MINE-DESTROYER.

1,217,812.

Specification of Letters Patent. Patented Feb. 27, 1917.

Application filed August 28, 1916. Serial No. 117,314.

To all whom it may concern:

Be it known that I, HARRY O'GRADY, a citizen of the United States, residing at Westbourne, in the county of Campbell and State of Tennessee, have invented new and useful Improvements in Torpedo-Catchers and Mine-Destroyers, of which the following is a specification.

This invention relates to improvements in 10 torpedo catchers and mine destroyers for war ships, one object of the invention being to provide an improved torpedo net arranged around the vessel and means to raise and lower the torpedo net as required; an- 15 other object being to provide a mine de- 20 structing apparatus which may be arranged at the bow of the vessel and employed for destroying mines ahead of the vessel and which mine destroyer may also be removed from the vessel's bow when desired.

The invention consists in the features of construction, combination, and arrangement of devices, hereinafter fully described and claimed.

25 In the accompanying drawings:—

Figure 1 is an elevation of a vessel pro- 30 vided with a torpedo net and also provided with a mine destroyer in accordance with my invention.

Fig. 2 is a plan of the same.

Fig. 3 is a rear elevation of the same.

Fig. 4 is a detail elevation.

Figs. 5 and 6 are detail sectional views 35 of the mine destroyer.

Fig. 7 is a detailed elevation of one of the net supporting devices.

The hull of a vessel is indicated at 1 and in accordance with my invention is pro- 40 vided on its sides and at suitable spaced points with net supporting brackets 2 which are pivotally mounted as at 3 and are ar- 45 ranged to be turned outwardly from the vessel or swung inwardly against its sides as required. Each bracket is provided with an outwardly extending, net supporting arm 4, and is also provided with a brace 5 for said arm.

The arm 4 is pivotally connected at its inner end as at 4^a to a member 4^b which is 50 secured on the vertical pivotal member of the bracket. Hence the arm may be raised and lowered independently of the bracket, the latter being limited to horizontal pivotal movement. The bracket is provided at its 55 upper corner with a rest 5^a to receive the arm. The bracket with its independently

pivotedly mounted supporting arm is shown in detail in Fig. 4.

On opposite sides of the bow are support- 60 ing frames 6 which are pivotally mounted as at 7 and may also be swung outwardly from or inwardly against the sides of the vessel. A torpedo net 8 is stretched along the sides and across the stern of the vessel and has its upper side attached to the arms 65 of the brackets 2 as at 9 and has its front ends attached to the frames 6 as at 10. The torpedo catching net is here shown as made of chains. It may, however, be made of any suitable material. 70

Rods 11 are arranged intermediate the brackets 2 and are bolted to the sides of the vessel as at 12. Hoisting links 13 are piv- 75 otally connected to said rods as at 14 and their outer ends are pivotally connected to the upper side of the net at points between the brackets. Hoisting means, such for in- 80 stance as winches 15, are provided on the vessel and hoisting ropes 17 are attached to the outer ends of the links and also to the hoisting means and enable the netting to be raised or lowered as desired.

To swing the chain outwardly from the sides of the vessel, I provide cables 19 which are attached to the frames 6 and pass 85 through suitable pulleys 20 and are connected to suitable winches or other like devices such as are indicated at 21. When these cables are drawn, the ends of the net are pulled forwardly and hence the brack- 90 ets, the frame 6, and the intermediate sup- porting links are also swung forwardly and extended outwardly from the sides of the vessel thereof spacing the net from and around the vessel and stretching the net to 95 enable it to successively withstand and catch torpedoes and prevent the torpedoes from injuring the vessel. At the stern, at opposite sides, I also provide stretching links 23 which are pivotally connected to the vessel 1 and are also connected to the upper side of the net.

The net may also, within the scope of my invention be provided with means for hoist- 100 ing and arranging it above the upper deck of the vessel to afford protection against air ships.

From the foregoing description, taken in connection with the accompanying draw- 11 ings, the advantages of construction and of the method of operation will be readily apparent to those skilled in the art to which

the invention relates, and while I have described the principles of operation of the device together with the device which I now consider to be the best embodiment thereof, I desire to have it understood that the device shown is merely illustrative and that such changes may be made when desired as are within the scope of the appended claim.

10 Having described the invention, what is claimed is:

A vessel, a supporting bracket pivotally

mounted at one side of the vessel for horizontal angular movement to enable said bracket to be swung outwardly from or moved toward the side of the vessel, and a net supporting arm mounted for movement with the bracket and also for vertical pivotal movement, said arm being when lowered carried by said bracket.

In testimony whereof I affix my signature.

HARRY O'GRADY.
